UNITED STATES PATENT OFFICE.

WILLIAM C. GREGG, OF NEWBURGH, NEW YORK, ASSIGNOR TO THE GREGG COMPANY, LTD., A CORPORATION OF NEW YORK.

RAILWAY-TIE FASTENING.

No. 826,242.

Specification of Letters Patent.

Patented July 17, 1906.

Application filed November 8, 1905. Serial No. 286,395.

To all whom it may concern:

Be it known that I, WILLIAM C. GREGG, a citizen of the United States, residing at Newburgh, in the county of Orange and State of New York, have invented certain new and useful Improvements in Railway-Tie Fastenings; and I do declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to metallic railway-ties; and it has for its object to provide means for fastening the rails to the ties which is simple, composed of the minimum number of parts, and strong and capable of quick application.

To the accomplishment of the foregoing and such other objects as may hereinafter appear the invention consists in combining with the tie and rail a fastening consisting of a U-shaped bolt having a hook-shaped head adapted to lap over the base of the rail at one side and having the other end threaded and extended so as to lie opposite to the other side of the base, so that a nut applied thereto may bear directly upon the top surface of the base, so that when tightened it will draw the hook-shaped head against and down upon the base at one side of the rail and at the same time bear down upon the other side of the base, and thus securely fasten the rail to the tie.

Figure 1 is a perspective of one form of tie, showing a rail clamped thereto by the improved fastening. Fig. 2 is a vertical section through the rail and tie with the fastening-bolt in full lines. Fig. 3 is a perspective of the preferred form of bolt and its nut, and Fig. 4 is a plan of a portion of a tie.

In the accompanying drawings the number 1 designates a rail of an approved type, and 2 a tie made of channeled metal of any approved design or shape in cross-section, which tie is formed with two holes or openings 3 and 4, located so that one will be on

each side of the base 5 of the rail. The bolt-fastening is designated by the numeral 6 and is practically a U-shaped bolt formed with a hook-shaped head 7, adapted to pass through, say, the hole 3 in the tie and bear against the rail-base and having its opposite end threaded and adapted to pass up through the other hole 4 and to lie alongside the edge of that side of the base of the rail, so that when a nut 8 is applied to the threaded end and screwed down it will lap over and bear directly upon the top surface of the base of the rail in such manner as to cause the bolt by its hook-shaped head at one end and by its nut at the other to securely clamp and fasten the rail to the tie. In the preferred form the threaded end of the bolt is deflected or inclined to a perpendicular, so that when the nut is screwed down it will not only lap over and bear down upon the base of the rail, but will have an extended bearing thereon, and may also bear down upon the top of the tie, thus affording two bearing-points for the nut and avoiding the necessity of employing washers or filling-blocks between the nut and top of the tie or top surface of the rail's base. This also avoids the necessity of any special construction to the top of the tie to receive either the base of the rail or the nut. This forms a secure and efficient fastening composed of the fewest number of parts and enables the tightening-nut to bear directly upon the rail-base with an extended bearing thereon and conforming to the inclination of the top surface of the rail-base, so as to afford a broader bearing for the nut against the rail-base, and while thus affording a most efficient fastening it materially reduces the cost of railroad construction. The feature of deflecting the end of the bolt from a perpendicular can be employed whether one or both ends of the bolt have nuts applied thereto, as will be apparent, without departing from this feature.

Having described my invention and set forth its merits, what I claim is—

The combination with a rail and rail-tie having holes located at opposite sides of the rail-base, of a fastening consisting of a bolt

having a hook-shaped end passing through one of the holes in the tie and overlapping the rail-base and provided with a nut at the other end overlapping the edge of the rail-base and bearing directly against the top of said base to clamp the rail to the tie, substantially as described.

In testimony whereof I affix my signature in presence of two witnesses.

WILLIAM C. GREGG.
